UNITED STATES PATENT OFFICE

122,740

DESIGN FOR A PLEATED FABRIC

Joseph Frischer, Long Beach, N. Y.

Application July 13, 1940, Serial No. 93,603

Term of patent 3½ years

To all whom it may concern:

Be it known that I, Joseph Frischer, a citizen of the United States and resident of the county of Nassau, city of Long Beach, and State of New York, have invented a new, original, and ornamental Design for a Pleated Fabric, of which the following is a specification, reference being had to the accompanying drawing, forming part thereof.

The figure of the drawing is a top plan view of one side of a fabric embodying my pleated design.

The opposite side of the fabric comprises the complementary portions of the pleats of the side shown in the drawing.

I claim:

The ornamental design for a pleated fabric, substantially as shown and described.

JOSEPH FRISCHER.
